UNITED STATES PATENT OFFICE.

DANIEL GLENN, OF DEL RIO, TEXAS.

SCREW-JACK HEAD.

SPECIFICATION forming part of Letters Patent No. 610,045, dated August 30, 1898.

Application filed April 8, 1898. Serial No. 676,362. (No model.)

To all whom it may concern:

Be it known that I, DANIEL GLENN, of Del Rio, in the county of Val Verde and State of Texas, have invented a new and Improved 5 Screw-Jack Head, of which the following is a full, clear, and exact description.

My invention relates to an improvement in screw-jack heads by which the same are provided with ball-bearings and the parts so locked together that they cannot separate, the locking mechanism being used also as a 10 brake to prevent the jack from running backward.

The invention consists of the novel features 15 of construction which will be hereinafter described and claimed.

Reference is to be had to the accompanying drawings, forming a part of this specification, in which similar characters of reference indicate 20 corresponding parts in all the figures.

Figure 1 is an elevation of a jack with the head in section. Fig. 2 is a section taken upon the line 2 2 of Fig. 1, and Fig. 3 is an enlarged detail section on the line 3 3 in Fig. 2.

25 The device is applicable to screw-jacks, but may be applied to any other form of jack or to similar mechanism in which a shaft revolves and is to be locked to a stationary head. The jack, as herein shown, is mounted upon 30 a frame A, which may be of any suitable construction. Upon the upper end of said frame is mounted a nut C, through which operates the threaded shaft B. As herein shown the nut is provided with ball-bearings D, the 35 balls lying between the faces of the thread on the nut and shaft. This, however, forms no part of my present invention.

At the upper end of the shaft is a fixed head E, which may be an integral part of the shaft 40 or secured thereto. The upper portion of this head is provided with a peripheral groove e, and the upper surface of the head is provided with a circular groove adapted to receive the balls L, which form a bearing between 45 the fixed head E and the rotatable head G. The head G is provided on its under surface with a recess or socket adapted to embrace the upper end of the head E, and the inner surface of the side wall of this 50 socket is provided with a groove g, adapted to register with the groove e when the two parts are placed in position.

Within the groove g is placed a set of locking-blocks F, made as segments of a ring and fitting snugly in the groove. The depth of 55 the groove g in the rotatable head is such as to permit of the blocks F being entirely received in said groove, so that the head G may be removed from the head E. The blocks F are forced inward by means of a series of set- 60 screws H', which pass through the flange at the lower end of the head G. These screws force the blocks F into the groove e in the head E, and thus lock the two parts E and G together, while permitting rotation of one 65 upon the other. One of these blocks, as the block F', is engaged by a special set-screw H, which has a head extending outside the head G, so that it may be engaged by a wrench. By setting this screw up tighter than ordinarily the block F' may be forced into the 70 groove e, so as to prevent rotation of the two heads upon each other. This block F' will thus act as a brake to prevent the jack from running down. The head G is preferably 75 provided with a rounded or hemispherical upper end, upon which is placed a cap I, having a socket fitting over the rounded end of the head, and a flat upper surface. This cap is secured in place by set-screws J, which 80 pass through the lower edge of the cap and enter a slot g' in the upper portion of the head G. The slot g' is of such width that the set-screws J will only partially fill the same, and thus permit of the rocking of the cap upon 85 the head.

Having thus fully described my invention, I claim as new and desire to secure by Letters Patent—

A screw-jack, having a threaded shaft terminating at one end in a peripherally-grooved head, a bearing-head recessed to fit over said head and having an internally-opening groove in the wall of said recess adapted to register with the groove in the shaft-head, locking-blocks fitting said grooves and holding the two parts together, the groove in the bearing-head being of a depth to entirely receive the blocks, and set-screws in the bearing-head and engaging the locking-blocks.

DANIEL GLENN.
